SPEED CONTROL OR GOVERNOR FOR
REVOLVING DOORSBurns H. Uhrich, Independence, Kans., assignor
to The Atchison Revolving Door Co., Independence, Kans., a corporation of Delaware

Application August 29, 1933, Serial No. 687,377

5 Claims. (Cl. 20—18)

The present invention relates to a speed control or governor for revolving doors and has for its object to provide a speed control or governor of simple construction, comprising fluid pressure speed checks and inter-connecting operating mechanism so arranged that they co-operate with each other to insure uniform and equalized resistance at all points as the door is revolved in operation, and to automatically increase the resistance to the revolution of the door should an attempt be made to revolve the door at an excessive speed.

A further object of the invention is to so construct and arrange the device that the wings of the door may be collapsed and moved to one side when it is desired to dispense temporarily with the use thereof.

To the above ends the present invention consists of the speed control or governor for revolving doors and of the devices and combinations of devices which will be hereinafter described and claimed.

The invention is shown in the accompanying drawings in which

Figure 1 shows a fragmentary portion of the upper part of a revolving door and the speed control or governor, with portions of the superstructure in longitudinal and diametrical sections;

Figure 2 shows a fragmentary view of the supporting track and the speed control governor supported therein, all the parts being shown in top plan view with the right-hand trolley wheels partially broken away;

Figures 3, 4 and 5 show in plan view the inter-connecting operating mechanism between the door and the fluid pressure checking devices, the different views showing the parts in various positions during the operation thereof;

Figure 6 is a sectional view of one of the fluid pressure checking devices taken on a diametrical line cutting the operating shaft and showing the double acting piston and other parts in plan view.

Similar reference characters will be employed throughout the specification and drawings to designate corresponding parts.

In the drawings 1 is a supporting spindle carrying the wings 2 of the door connected thereto in any usual manner to revolve therewith and to be turned thereon so as to have a collapsing movement; the spindle 1 being supported at its lower end in any suitable manner and at its upper end in a bearing mounted on the truck 3, and may be provided with the usual circular plates 4 to which the wings 2 are directly connected and

supported and to which they may be locked and held in a radial position, there being usually two such plates 4, the lower one in the present case, as well as the mounting for the lower end of the spindle or shaft 1 and the bearing carried by the truck 3 which supports part of the weight of the spindle 1 so as to permit the entire structure to revolve freely, are not specifically shown; but they all may be of any usual or preferred construction well known to those familiar with this art.

The ceiling 5 of the door closure, usually circular in form, is provided with a radial slot 6 extending from a point corresponding to the axial center, towards the periphery and the side wall 15 of the door structure, not shown. This is for the purpose of permitting the spindle 1 and the revolving door when collapsed to be moved to one side, leaving the door opening clear, all in the usual manner. Of course it is understood that the lower end of the spindle and its support will partake of this lateral or radial movement.

Above the ceiling 5 is a trough-like box 7 extending in a diametrical direction on a line which will bring the axial line of the shaft 1 in the center of the longitudinal central portion thereof. The box 7 comprises a base 8 and upwardly extending side walls 9 only one of which is shown in Figure 1, but both of which are shown in Figure 2. The base 8 is slotted as at 10, corresponding to the slot 6 in the ceiling 5, thus permitting the spindle 1 to be moved freely in collapsing the door.

The fluid pressure checks are carried by the truck 3 which at its opposite ends is provided with trolley wheels or rollers 11 arranged to roll over the base 8 of the box 7. Preferably the rollers 11 will be mounted on inclined axes as indicated, so that their peripheries will contact with the angle formed by the base 8 and the walls 9 of the box 7, thereby preventing any frictional contact of the faces of the rollers 11 with the inner face of the walls 9 and insure the reduction of friction to a minimum.

As hereinbefore pointed out, the truck 3 at its forward end carries the top supporting bearing for the spindle 1, a portion of the bearing being shown at 12. The truck 3 has a vertical side wall 13 to which are bolted the brackets of the fluid pressure checks 15, and 15'. These checks also may be supported upon a horizontal plate 16 forming a part of the truck, as indicated by dotted lines 17 in Figure 1, whereby the checks 15 and 15' are held in alignment with each other.

and rigidly supported against all movement with relation to each other and the truck 3.

As shown in Figure 6, the checking devices 15 and 15' are of the fluid pressure type, each of them comprising a cylindrical chamber filled with any desirable fluid 18, and a reciprocating double piston 19 and suitable check valves 20 at opposite ends. Each of the pistons 19 is provided with a rack 21 which engages with a mutilated gear 22 mounted on a shaft 23, the arrangement being such that a partial rotary movement of the shaft 23 is permitted to reciprocate the piston 5, displacing the fluid 18 which will resist, of course, the movement of the piston to that extent limited by the adjustment of the check valves 20.

The casings of the checks 15 and 15' also have an upper circular chamber which communicates by means of a chamber 25 and an opening 26 with the piston chamber. (See Figures 1, 2 and 6.) The shafts 23 which carry the mutilated gears 22 project through the top of the circular portion 24 of the casing 5, and crank arms 27 and 28 are fixedly secured to the upper end of said shafts. The upper end of the spindle 1 is provided with a crank 29 which rotates therewith. By means of the link 30 the crank 29 is connected to the crank arm 27 of the check 15, the said arm 30 being pivotally connected at 31 to the crank 29 and at 32 to the crank 21. The crank 29 is also pivotally connected at 31 to a link 33 which in turn is pivotally connected at 34 to a link 35 which is pivotally connected at 36 to the crank arms of the check 15'. The links 33 and 35 are also pivotally connected to a toggle link 37 which is pivotally mounted at 38 to a boss carried by the side wall 13 of the trolley.

By this arrangement the rotary movement of the spindle of the door will completely rotate the crank 29, imparting oscillating movements through the links 30, 33 and 35 to the respective crank arms 27 and 28, thus reciprocating the pistons in the check devices 15 and 15' and controlling the speed of rotation of the door and preventing its being rotated at an excessive and dangerous speed. In the normal operation of the door at a limited speed the operation of the checks 15 and 15' puts practically no resistance on the door, but as soon as the revolution of the door exceeds a normal speed the reciprocations of the pistons in the checks 15 and 15' are slowed up by the resistance offered by the fluid contained in the checks.

It is important to notice that while the checks operate simultaneously, yet, by the arrangement of the cranks and levers as shown, the operations will vary with each other in so far as direction, speed and extent of movement are concerned; thus the checks will complement each other and there will be no variation of the checking movement on the door itself.

This will be clearly understood by an inspection of Figures 2, 3, 4 and 5, the operating connections being shown in four different positions. The cranks 29 will revolve with the door spindle 1 in a counter clockwise direction as indicated by the arrows in Figures 2, 3, 4 and 5. In these figures the crank 29 and the various links and levers are shown in relative positions during a complete reciprocation of the pistons in the checks 15 and 15'. In Figure 2 the piston in the check 15 has completed approximately three-quarters of a stroke to the right, while the piston in check 15' is at the end of its stroke to the right. In Figure 5 the crank 29 has moved to a

position where the piston in the check 15 is at the end of its stroke to the right, while the links 33 and 35 and the toggle link 37 have moved the crank arm 28 and the piston in the check 15' to the left for a part of its stroke. In Figure 3 the crank 29 by means of the link 30 and the crank arm 27 has moved the piston in the check 15 for three-quarters of the distance in its stroke to the left, while the position of the crank arm 28 indicates that the piston in the check 15' is at the end of its stroke to the left. Figure 4 shows the crank 29 in a position still further on its path of travel and the crank arm 28 fully extended towards the left with the piston in the check 15' at the end of its lefthand stroke, while the crank arm 28 has traveled approximately one-quarter of the distance back on its righthand stroke. It will thus be clear that there will be a constant resistance against the revolution of the crank 29, which, under normal conditions, and where the door is not revolved at excessive speed, will provide a smooth operation; but as soon as the speed of rotation exceeds a predetermined limit the door will be automatically checked by the resistance of the reciprocating pistons. At no point in the revolution of the door are both pistons at the end of their stroke at the same instant. When the piston in check 15 has reached the end of its stroke and is starting back, the piston in the check 15' is approximately at the middle of its stroke. This avoids any jerky action in the rotation of the door, since at all times there is sufficient resistance exerted by the checks.

It will of course be noted that by placing both checks 15 and 15' at one side of the spindle 1 there will be no interference with the movement of the collapsed door towards the left, as shown in Figure 1 of the drawings, and for this reason the arrangement shown is the preferred form; but in so far as the controlling or governing action of the device is concerned they would be present even though one of the checking devices was placed on one side of the spindle and the other checking device on the other side of the spindle. It is the timed operation in tandem of the two checks which constitutes the important part of the invention.

The apparatus will of course embody any suitable latching mechanism such as the lever or plate 39 pivotally mounted to swing up and down as at 40 and which carries diametrically opposite lugs 41 arranged to engage notches in plates supported upon the inner face of the walls 9 of the support 1, but such latching mechanism in and of itself constitutes no part of the present invention.

It will be understood of course that the particular construction of the checking devices is not of applicant's invention, but the arrangement of them in pairs and so operating them that the operation of one will overlap that of the other, or in tandem, as it were, thereby producing a constant, smooth check or control of the speed of rotation of the door, is of the essence of the present invention. Also, while the arrangement shown is that preferred by the applicant in that it permits the door to be fully collapsed and moved to one side, the invention includes an arrangement whereby the tandem checks may be placed at diametrically opposite sides of the door spindle and produce the same effect in so far as its speed control function is involved.

I claim:

1. In combination, a revolving door, a speed

75

control or governor comprising two fluid pressure checks, and means connected with the door spindle to operate the checks simultaneously in overlapping time relation.

- 5 2. In combination, a revolving door, a speed control or governor comprising two fluid pressure checks both disposed at one side of the door spindle in line with each other, a crank carried by said spindle, a link connecting said crank with one of the fluid pressure checks, and toggle links connecting said crank with the other of said fluid pressure checks.
- 10 3. In combination, a revolving door comprising a vertically disposed spindle, a sliding truck connected to and arranged to be moved laterally with said spindle, a pair of fluid pressure check devices mounted on said truck in alignment with each other, a crank carried by said spindle, and connections between said crank and said checks to operate them simultaneously but in overlapping time relation to each other.

4. In combination, a revolving door, a speed control or governor comprising two fluid pressure checks both disposed at one side of the door spindle in line with each other, each of said checks provided with an oscillating arm, a crank carried by the spindle at its upper end, a link pivotally connecting said crank to the oscillating arm of one of the checks, and a toggle link construction pivotally connecting the crank and the oscillating arm of the other check. 10

5. In combination, a door having radial wings, a revolving spindle on which said door is mounted, a crank on said spindle, two speed control devices, an oscillating arm on each of the speed control devices, and connecting means between 15 the spindle, crank, and the oscillating arms of the speed control devices, whereby the rotation of the door moves the said arms in certain time relation so that they will reach their highest rate of speed at different intervals. 20
